SAFETY RAZOR

John H. Hotson, Woodside, N. Y.

Application October 7, 1935, Serial No. 43,821

18 Claims. (Cl. 30—41)

The invention relates to razors, and more particularly to that type commonly known as safety razors.

The principal object of the invention is to provide simple, efficient and economical means whereby shaving application of either the soap or cold cream type, which accumulates on the razor, may be replaced on the face for reuse. Further objects and advantages of the invention will be in part set forth in the following specification, and in part will be obvious therefrom without being specifically pointed out, the same being realized and attained as hereinafter more fully described or as pointed out in the claims hereof.

With the above and other objects of the invention in view, the invention consists in the novel construction, arrangement and combination of various devices, elements and parts, as set forth in the claims hereof, certain embodiments of the same being illustrated in the accompanying drawings and described in this specification.

In the accompanying drawings,

Fig. 1 is an end view, partly in section, of an embodiment of the invention employing hinged pushers operated by a sliding sleeve mounted on the handle;

Figs. 2 and 3 are side and plan views respectively of the cap shown in Fig. 1;

Fig. 4 is a side view of the central handle rod shown in Fig. 1;

Fig. 5 is an end view of the sleeve and guard shown in Fig. 1;

Fig. 6 is a view of the sliding sleeve shown in Fig. 1, and viewed from the same direction;

Fig. 7 is another view of the same, as it would be seen from the side of the razor;

Fig. 8 is a plan view of Fig. 5;

Fig. 9 is a side view of the helical spring operating between the two sleeves;

Fig. 10 is a detached view of one of the pushers, the same being viewed from the side toward the handle;

Fig. 11 is a view of the same from the side away from the handle;

Fig. 12 is a cross section of one of the pushers;

Fig. 13 shows a hinge pin for attaching a pusher to a guard;

Fig. 14 is an end view of another embodiment of the invention, in which a rigid pusher is operated by a lever pivoted on the handle;

Fig. 15 is a side view of the embodiment shown in Fig. 14;

Fig. 16 is an end view of another embodiment of the invention, in which a hinged pusher is operated by a pivoted lever on the handle;

Fig. 17 is a side view, partly in section, of the form shown in Fig. 16;

Fig. 18 is a detail view showing the manner in which the pusher is hinged to the bottom of the sleeve which forms part of the handle shown in Figs. 16 and 17;

Fig. 19 is a detached view of the pusher shown in Figs. 16 and 17;

Fig. 20 is a cross section of the same;

Fig. 21 is an end view of another embodiment of the invention, in which a rigid pusher is operated by a resilient lever; and

Fig. 22 is a detached view of the pusher and lever shown in Fig. 21.

In carrying my invention into effect in the embodiment thereof which is illustrated in Figs. 1 to 13 inclusive, and which is regarded as the preferred form, it will be seen that there is provided a cap 30 (see Figs. 1, 2 and 3), provided with the usual guide lugs 31, and with a threaded shank 32 of sufficient height easily to engage a threaded socket 33 in the lower end of the rod 34.

This rod 34, shown separately in Fig. 4, forms the innermost member of the compound handle, and besides having the threaded socket 33, it is provided at its lower end with an annular groove 35 and at its upper end with a knob 36 having shoulders 37 and 38.

Referring now to Figs. 5 and 8, I provide a guard 39 having the usual teeth 40, and being also provided on its upper side with hinge knuckles 41. Permanently attached to the guard 39 is a fixed sleeve 42 which forms the intermediate member of the compound handle. The rod 34 is rotatably mounted inside the sleeve 42, with the shoulder 37 bearing against the upper end 43 of said sleeve 42, and is secured in this position by a pin or screw 44 inserted through a perforation 29 in the sleeve 42 and engaging the groove 35. The rod 34 and sleeve 42 are thereby permanently assembled with relation to each other longitudinally, while the rod 34 may be rotated within the sleeve 42 in order to remove or replace the cap 30. A blade 45, shown in Fig. 1, is removably clamped between the cap 30 and guard 39. The fixed sleeve 42 is also provided with a shoulder 46, and with longitudinal slots 47 open at the end 43 and extending downwardly therefrom.

Referring now to Figs. 6 and 7, I provide a sliding sleeve 48, which forms the outermost member of the compound handle. This sleeve 48 is provided with inwardly projecting lugs 49, which may easily be formed by cutting out and bending inward portions of the metal from which the

sleeve is formed. These lugs 49 are adapted to engage with the slots 47 of the sleeve 42. The sleeve 48 is thereby adapted to be slidably mounted outside of the sleeve 42, but held against rotating with reference thereto. The sleeve 48 is permanently assembled with the other parts of the handle, and its sliding movement is limited upwardly by the shoulder 38 on the knob 36, which shoulder engages the upper end 50 of the 10 sliding sleeve 48, as shown in Fig. 1. The lower ends of the sliding sleeve 48 are provided with downwardly extending projections 51, each provided at its lower end with a slot 52.

A helical spring 64 is provided, shown separately in Fig. 9 and in its operative position in Fig. 1. This spring lies outside of the sleeve 42, within the space above the shoulder 46, and inside the sleeve 48. This spring 64 operates expansively downward against the shoulder 46 and upward against the lugs 49, thereby tending to hold the parts in the position shown in Fig. 1. The upper end of the spring 64 is closed against itself to avoid the possibility, should the spring rotate on its axis, that the lugs 49 might become 25 entangled with the coils.

Referring now to Figs. 10, 11 and 12, I provide hinged pushers 53 each having open knuckles 54, closed knuckles 55, and recesses 56 adapted to clear the knuckles 41 on the guard 39. Pins 57, 30 one of which is shown separately in Fig. 13, pass through the knuckles 41, 54 and 55, and the pushers 53 are thereby pivotally mounted on the guard 39. One end of each pin 57 is bent as shown at 58, and when the device is assembled 35 this bent end is snapped into a perforation 59 in one of the open knuckles 54, and the pin is thereby prevented from slipping. The open knuckles 54 serve to protect the ends of the pins, while leaving them accessible whenever the removal of 40 the pins become necessary in order to disassemble the device.

Each pusher 53 is provided with a link 60, the position of which when the device is assembled is shown in Fig. 1. In assembling the device 45 the free end 61 of this link, which bears resiliently against the pusher 53, is snapped through one of the slots 52 provided at the bottom of the sliding sleeve 48. By this means the pushers are operatively connected with the sliding sleeve 48, and 50 ordinarily are held in the position shown in Fig. 1 by the action of the spring 64. When, however, the sleeve 48 is pushed downward, the pushers will swing into a position parallel with and close to the upper surface of the guard 39, 55 and any accumulation of shaving application between the pushers and the top of the guard will be forced out.

The portion 62 adjacent the free edge of each pusher 53 is bent in the manner shown particularly in Figs. 1 and 12, in order that when the pushers are operated those portions of the same which project beyond the edge of the guard 39 will not scrape against the face. Each of the 60 pushers 53 is also provided with a row of projections 63 adapted when the pusher is operated to enter the spaces between the teeth 40 of the guard 39 and clear the same of shaving application, which is particularly desirable when application of the cold cream type is employed, since 65 this type is generally applied sparingly to the face.

In the operation of this embodiment of my invention, the shaving strokes are performed in the 70 ordinary way, the handle being held lightly so

that the spring 64 may operate to hold the pushers 53 away from the guard. Under these conditions the device will operate in a manner similar to any other safety razor; with the advantage, however, that owing to the longitudinal resiliency between the sleeve 48, which is the part directly held in the hand, and the cutting portion, this cutting portion upon encountering any protuberance on the face will be more likely to slide over the same instead of cutting into it. 10

Between each shaving stroke the razor is slid backward over the face, the sleeve at the same time being pressed downward against the spring 64. The result of this is to force out the shaving application which has accumulated between the 15 guard 39 and pusher 53, as well as between the teeth 40 of the guard 39; and to spread this shaving application over the face in such a manner that it may be used again with the next shaving stroke. 20

This embodiment of my invention is so constructed that in learning to use the same, no change of habit is required in performing the delicate part of the operation, the shaving stroke itself, and this if anything is made slightly easier; 25 while the operation required on the return stroke of the razor has been so arranged as to be performed in a simple, natural and easy manner. The permanent assembly of the pushers and compound handle leaves the operations required in 30 removing or inserting a blade no more difficult than in any other razor, time thus being conserved and confusion avoided. It is possible, however, when required for the purpose of repairs, replacements or an occasional thorough cleaning, 35 to disassemble the device completely by removing the pin or screw 44 and the hinge pins 57, and by snapping the links 60 out of the slots 52.

Referring now to the embodiment shown in Figs. 14 and 15; in order that the description of 40 this embodiment may be more easily understood, all parts which are analogous either in structure or function to corresponding parts shown in Figs. 1 to 13 inclusive, have been indicated by corresponding numerals to which the number 50 has 45 been added in each case.

As shown in Figs. 14 and 15 I provide a cap 80, having guide lugs 81 and a threaded shank 82; a rod 84 having a threaded socket 83 adapted to engage the threads of the shank 82, and also 50 having a knob 86 with a shoulder 87; a blade 95; and a guard and sleeve assembly comprising a guard 89 with teeth 90, and a sleeve 92 the upper end 93 of which will bear against the shoulder 87 when the razor is assembled. I also provide a 55 bent lever 98, pivoted to the sleeve 92 at 115; and a flat spring 114 between the upper end of the lever 98 and the sleeve 92. The pusher 103 in this embodiment is not hinged, but rigidly mounted on the lower end of the lever 98. The spring 60 114 ordinarily holds the lever 98 and pusher 103 in the position shown by the full lines in Fig. 14, but when the top of the lever 98 is pinched against the sleeve 92 the parts will assume the position 65 shown by the dotted lines in said Fig. 14.

Referring now to the embodiment shown in Figs. 16 to 20 inclusive; all the parts which are analogous either in structure or function to corresponding parts shown in Figs. 1 to 13 inclusive, have been indicated by corresponding numerals 70 to which the number 100 has been added in each case.

As shown in said Figs. 16 to 20 inclusive, I provide a cap 130 having guide lugs 131 and a thread- 75

ed shank 132; a rod 134 having a threaded socket 133, and having a knob 136 with a shoulder 137; a blade 145; a guard 139 having teeth 140; and a sleeve 142 the upper end 143 of which is adapted when the razor is assembled to bear against the shoulder 137.

In this embodiment the guard 139 and sleeve 142 are not integral. The lower end of the sleeve 142 is provided with an integral T-bar 166 having 10 hinge knuckles 141. I provide a hinged pusher 153 with a bent portion 162 and hinge knuckles 155. The pusher is pivoted to the T-bar 166 by a hinge pin 157 passing through the knuckles 141 and 155, and is provided with a row of projections 163 adapted when the pusher is operated to clear the interstices between the teeth 140 of the guard 139.

The pusher is operated by a lever 148, pivoted to the sleeve 142 at 165, and ordinarily held in 20 its inoperative position by a spring 164 operating between said sleeve 142 and lever 148. The lower part of the lever 148 is bifurcated at 167, and the free end of each bifurcation is notched at 152 (see Fig. 16). The pusher 153 is provided with up- 25 turned perforated lugs 160 adapted to be engaged by the notched ends 152, and the pusher 153 is thereby operatively connected with the lever 148.

Referring now to the embodiment shown in Figs. 21 and 22; all the parts which are analogous 30 either in structure or function to corresponding parts shown in Figs. 1 to 13 inclusive, have been designated by corresponding numerals to which the number 150 has been added in each case.

In said Figs. 21 and 22 I have selected for the 35 purpose of illustrating the construction and operation of this embodiment a safety razor employing a blade of the single edged type. This razor is provided with a cap 180, a blade 195, and a guard 189 having a sleeve 192 integral therewith. 40 The cap 180 is not entirely removable, but pivoted at 218 to the guard and sleeve assembly, and operated in any suitable or conventional manner by a rod 184 rotatably secured within the sleeve 192. This rod 184 is provided with a knob 186.

45 Riveted to the sleeve 192 at 219 is a resilient lever 198, having its lower portion 217 bent approximately at right angles to the sleeve 192 and bifurcated in order to straddle the same, and provided at its free end with a pusher 203. The pusher, fork and lever assembly may be integral, and is shown separately from any razor in Fig. 22. This assembly when at rest occupies the position shown by the dotted lines in Fig. 21, but when the lever 198 and sleeve 192 are pinched together, the 50 parts will assume the position shown by the full lines in Fig. 21. Since the pusher 203 lies on the opposite side of the sleeve 192 from the lever 198, when the lever 198 is pressed toward the sleeve 192, the pusher 203 is moved away from it.

60 In each of the three embodiments shown respectively in Figs. 14 and 15, Figs. 16 to 20 inclusive, and Figs. 21 and 22, the method of using the razor is the same. The shaving strokes are performed in the usual way, while on the backward 65 strokes of the razor the lever 98, 148 or 198 is pinched against the handle. The manner in which each of these embodiments respectively performs its function will now be obvious from what has been above set forth regarding their construction, and regarding the construction and mode of operation of the embodiment shown in Figs. 1 to 13 inclusive.

By employing my invention in any of its 75 embodiments, the user will be enabled to shave him-

self more rapidly than would otherwise be the case, since after making the initial application of shaving preparation, subsequent applications may be made by utilizing time and motions which would otherwise be wasted. He may also shave himself more economically, since he will be enabled to reutilize shaving application which is ordinarily thrown away, and he may also shave himself with greater comfort, since the face will be continuously supplied throughout the entire 10 operation with an adequate amount of shaving preparation, and need not become dry between successive applications by brush or fingers.

Other advantages of the invention will be obvious from what has been above set forth with regard to its construction and operation.

I do not limit myself to the particular details of construction set forth in the foregoing specification and illustrated in the accompanying drawings, as the same refer to and set forth only 20 certain embodiments of the invention. It is obvious, for instance, that any of the embodiments illustrated and described may be adapted for use with either of the types of razor illustrated, or with any other form of razor; and that in the 25 case of any razor having a double edged blade, the use of either a single or double pusher in connection with any embodiment of my invention is optional; and that other modifications may be made, within the scope of the appended 30 claims, without departing from the spirit and scope of the invention.

Having thus described my invention, what I claim as new and desire to secure by Letters Patent is as follows:

1. A safety razor holder comprising a guard, a handle, a pusher, and means adapted to move said pusher toward face to face contact with said guard, whereby accumulated shaving application may be removed from between said guard and 40 pusher.

2. A safety razor holder comprising a guard, a handle, and a pusher pivoted adjacent the junction of said guard and handle, and adapted to move accumulated shaving application from the 45 guard.

3. A safety razor comprising a guard, a blade, a handle, and a pusher pivoted adjacent the junction of said guard and handle, and adapted to move accumulated shaving application from the 50 guard, the free edge of said pusher being bent so as to form an angle with the main portion of said pusher.

4. A safety razor comprising a guard having teeth, a blade, a handle, and a pusher pivoted 55 adjacent the junction of said guard and handle, said pusher being provided with projections adapted to enter the interstices between the teeth of said guard and to push shaving application out of said interstices.

5. A safety razor holder comprising a guard, a handle, a pusher pivoted adjacent the junction of said guard and handle, and adapted to move accumulated shaving application from the 60 guard, and a spring adapted to hold said pusher in an inoperative position.

6. A safety razor holder comprising a guard, a handle, a pusher, means operatively connecting said pusher with said handle, and a spring operating against said handle and said connecting 70 means adapted to hold said pusher in an inoperative position.

7. A safety razor comprising a guard having teeth, a blade, a handle bearing a sleeve; a pusher pivoted adjacent the junction of said guard and 75

- 5 sleeve and operatively connected with said sleeve, said pusher being provided with projections adapted to enter the interstices between the teeth of said guard and to push shaving application out of said interstices; and a spring adapted to hold said pusher in an inoperative position.
8. A safety razor comprising a guard, a blade, a handle, a hinged pusher adapted to move 10 accumulated shaving application from the guard, and a sleeve slidably mounted on said handle and operatively connected with said pusher.
9. A safety razor comprising a guard, a blade, a handle, a hinged pusher, a sleeve slidably 15 mounted on said handle and operatively connected with said pusher, and a spring adapted to operate between said handle and sleeve and thereby hold said pusher in an inoperative position.
10. A safety razor comprising a guard, a blade, a sleeve mounted on said guard, a hinged pusher, a rod within said sleeve provided with means 20 adapted to hold said guard and blade in operative relation, and a second sleeve slidably mounted on said first named sleeve and operatively connected with said pusher.
11. A safety razor comprising a guard, a blade, a sleeve mounted on said guard, a hinged pusher, a rod within said sleeve and provided with means 25 adapted to hold said guard and blade in operative relation, a second sleeve slidably mounted on said first named sleeve and operatively connected with said pusher, and a spring adapted to operate between said sleeves and thereby hold 30 said pusher in an inoperative position.
12. A safety razor comprising a guard, a blade, a sleeve mounted on said guard, a hinged pusher, a rod within said sleeve provided with means 35 adapted to hold said guard and blade in operative relation, means adapted to permit said rod to rotate within said sleeve but to limit the longitudinal movement of said rod within said sleeve, and a second sleeve slidably mounted on said 40 first named sleeve and operatively connected with said pusher.
13. A safety razor comprising a guard, a blade, a sleeve mounted on said guard, said sleeve being provided with an annular shoulder and with a longitudinal slot, a second sleeve slidably 45 mounted on said first named sleeve and provided with an inwardly projecting lug adapted to enter said slot, a helical spring between said sleeves,

the ends of said spring bearing against said shoulder and said lug, a rod within said first named sleeve provided with means adapted to hold said guard and blade in operative relation, and a hinged pusher operatively connected with 5 said second named sleeve.

14. A safety razor comprising a guard, a blade, a sleeve mounted on said guard, said sleeve being provided with an annular shoulder and with a longitudinal slot, a second sleeve slidably 10 mounted on said first named sleeve and provided with an inwardly projecting lug adapted to enter said slot, a helical spring between said sleeves, the ends of said spring bearing against said shoulder and said lug, a rod within said 15 first named sleeve provided with means adapted to hold said guard and blade in operative relation, means adapted to permit said rod to rotate within said first named sleeve but to limit the longitudinal movement of said rod within said 20 sleeve, and a hinged pusher operatively connected with said second named sleeve.

15. A safety razor comprising a guard, a blade, a handle, a pusher pivoted adjacent the junction of said guard and handle, and a lever pivoted 25 on said handle and adapted to operate said pusher.

16. A safety razor comprising a guard, a blade, a handle, a pusher, a lever pivoted on said handle and adapted to operate said pusher, and a spring 30 operating against said lever and said handle and adapted to hold said pusher in an inoperative position.

17. A safety razor holder comprising a guard having teeth, a handle, a pusher pivoted adjacent 35 the junction of said guard and handle and provided with projections adapted to enter the interstices between the teeth of said guard and to push shaving application out of said interstices, and a lever secured to said handle and adapted 40 to operate said pusher.

18. A safety razor holder comprising a guard having teeth, a handle, a pusher provided with projections adapted to enter the interstices between the teeth of said guard and to push shaving application out of said interstices, means 45 operatively connecting said pusher with said handle, and a spring operating against said handle and said connecting means, said spring being adapted to hold said pusher in an inoperative 50 position.

JOHN H. HOTSON.
